J. L. MUELLER.
OIL CLOTH STAND.
APPLICATION FILED APR. 19, 1913.

1,144,229.

Patented June 22, 1915.

Fig. 1.

UNITED STATES PATENT OFFICE:

JOHN L. MUELLER, OF ST. LOUIS, MISSOURI.

OIL-CLOTH STAND.

1,144,229.

Specification of Letters Patent. Patented June 22, 1915.

Application filed April 19, 1913. Serial No. 762,245.

To all whom it may concern:

Be it known that I, JOHN L. MUELLER, a citizen of the United States, and residing at St. Louis, in the State of Missouri, have invented certain new and useful Improvements in Oil-Cloth Stands, of which the following is a specification.

This invention relates to display stands for oilcloth or like material.

10 This application is a continuation of my co-pending application Serial Number 693,387, filed April 26, 1912, as to subject matter, which is common to the two applications.

15 One of the objects of this invention is to construct a stand which will support rolls of oilcloth or like material so as to display the goods and permit easy removal and replacement thereof.

20 Another object is to provide means for holding and clamping the rolls in rolled up position while supported on the stand so as to display the pattern of the goods, which means is so constructed and arranged as to

25 permit easy removal and replacement of the rolls and permit the same to be placed close together so as to keep the size of the stand and the space occupied thereby down to a minimum.

30 Further objects will appear from the detail description taken in connection with the accompanying drawing, in which:

Figure 1 is a front elevation of a stand embodying this invention, Fig. 2 is a longitudinal vertical section on the line 2—2 Figs. 3 and 4, Fig. 3 is a section on the line 3—3 Fig. 1, Fig. 4 is a section on the line 4—4 Fig. 1, Fig. 5 is a detail view of one of the clamps, Fig. 6 is a section on the line 40 6 Fig. 1, and Fig. 7 is an enlarged detail view of the thrust bearing.

Referring to the accompanying drawings 10 designates a support or base provided with legs 11. This base is provided with a 45 boss 12 which is tapered to receive the threaded end of a hollow post 13 which extends vertically through the carrier, herein-after to be described, and forms a bearing therefor.

50 The carrier comprises an upper plate 14 and a lower plate 15 connected by a series (in this case four) of rods or bars 16 which are clamped to the plates by means of nuts 17. The plates and bars thus form together 55 a braced carrier of skeleton form. The lower plate 15 has formed therein a series

of shallow recesses sunk into the plate, while the upper plate has corresponding apertures 19 which extend entirely therethrough. These recesses and apertures form means for 60 vertically and laterally supporting the rolls 20 of oil cloth in the carrier.

The lower plate 15 has an aperture 21 formed therein which slips over the post 13. The upper end of the post has mounted 65 thereon a bracket 22 which slips over the end of the post and is secured in position thereon by means of a set screw 23. This bracket 22 has a lug 24 which extends through an aperture 25 in the upper plate 14 70 and is threaded to receive a nut 26 and a washer. The upper face 27 of the bracket 22 is machined to receive a roller thrust bearing 28 of well known construction. By means of this construction the carrier is 75 revolvably supported at its upper end on the upper end of the post 13.

80 A frame work or bracket comprising collars 30 mounted on the bars 16, and cross members 31 integral with the collars is secured in position about midway between the plates 14 and 15 by means of set screws 32 or in any suitable manner. A plate 33 is formed integral with the frame work and is connected to the cross members 18 by inclined-lugs 34 which raise the upper surface 85 of the plate 33 slightly above the collars 30 and the cross members 31. A series of clamps 35 are clamped on the plate 33 by means of screws 36 passing through a clamping ring 37, through the eyes 38 of the clamps and tapped into the plate 33. The clamps are thus positioned radially on the carrier. Each of these clamps is formed of 90 spring steel bent to form curved clamping arms 39 having rounded ends 40. These clamps may therefore be expanded to any desired extent but when released will automatically close to clamp the object placed between the clamping arms 39. The rounded ends 40 are slightly separated thereby 95 permitting the object to be clamped to be readily placed in position in the clamp.

100 A cover 41 has the lower edge thereof expanded as shown at 42 so as to take over 105 and rest on the plate 14. This cover is retained in position by means of clips 43 secured to the cover and adapted to be bent under the plate 14 as shown at 44. By means of this construction the cover may be 110 readily removed by bending out the clips 43. A card holding device 45 is mounted on the

cover. This holding device has spring arms 46 adapted to clamp and hold a card or sign 47.

In Fig. 1 the rolls are shown in position 5 in the revoluble carrier. The bottoms of the rolls rest in the shallow recesses 18 which vertically sustain the lower ends of the rolls and prevent lateral displacement. The upper

ends of the rolls extend through the recesses 10 or apertures 19 in the upper plate, and these apertures sustain the rolls at their upper ends. Rolls of oilcloth are generally shipped with the pattern turned in. It is desirable however, that the pattern be shown 15 when the rolls are displayed. To obtain this result the oilcloth is unrolled a foot or two, the end turned over and rolled up again so the roll is now placed in the stand the oilcloth will be held in position.

20 To remove a roll it is raised a short distance to clear the lower end from the recess 13; this lower end is then moved outwardly so as to cause it to clear the lower plate 15, and the roll is then dropped to cause the 25 upper end to disengage from the upper plate. The yielding construction of the spring clamps 35 is such as to permit the roll to be readily moved out as it is removed from the carrier in the manner indicated. The

30 distance between the ends 40 when the clamp is closed is sufficient, and these ends are rounded enough, so that a roll can be readily placed between the clamp arms without requiring these arms to be spread by hand. A 35 roll can thus be removed or replaced with one hand leaving the other hand free. Table oilcloth is generally furnished in rolls about four feet long. Now if such rolls are supported at their upper and lower ends only,

40 (which is desirable as it displays the full length of the rolls) the oilcloth is liable to unroll and bulge out at the center of the roll. By the provision of these clamps this 45 bulging out at the center is prevented so that the rolls will always be held neatly in rolled up position. In view of the fact that the clamps face and open and close circumferentially, not only can the rolls be readily removed and replaced, but this construction

50 also permits these rolls to be placed close together in the stand, thereby keeping the size of the stand down to a minimum. It will be noted that the carrier is suspended 55 at its upper end on the post 13; this construction not only renders the carrier stable but permits it to be easily revolved.

Rolls of oil cloth as made by different manufacturers, or even by the same manufacturer, vary in length from a standard. 60 Thus, oil cloth sold as 60 inches wide, may be 59 inches wide when made by one manufacturer and 61 inches when made by another manufacturer. This will cause the ends of the rolls to project different distances through the top plate, thus present-

ing an unattractive appearance. However, by providing a cover 41 of a depth of three inches or more, the tops of the rolls are covered, thereby presenting a neat appearance, at the same time permitting sufficient 70 free upward movement of the rolls to permit removal thereof from the stand without removing the cover.

It is obvious that various changes may be made in the details of construction without departing from the spirit of this invention and it is therefore to be understood that this invention is not to be limited to the specific construction shown and described.

Having thus described the invention what is claimed is:

1. An oilcloth stand comprising, a revoluble carrier, means on said carrier engaging the rolls for axially and laterally supporting one end of the rolls, means on said carrier engaging the rolls for laterally supporting the other ends of the rolls, and a series of radially facing and circumferentially opening and closing clamps on said carrier for detachably embracing the rolls intermediate their ends, constructed to hold the oilcloth in rolled up position while supported in the stand, whereby a roll may be moved by a combined axial and radial movement out of engagement with said 90 supporting and holding means to remove the same from said carrier.

2. An oilcloth stand comprising upper and lower plates, means connecting said plates to form a braced revoluble carrier, a base for revolvably supporting said carrier, said lower plate having a plurality of recesses constructed to receive and vertically and laterally support the lower ends of the rolls, and the upper plate having a plurality of apertures extending therethrough constructed to receive and laterally support the upper ends of the rolls, and radially facing and circumferentially opening and closing clamps adapted to embrace and clamp the rolls intermediate their ends, whereby said rolls are supported at their upper and lower ends, and whereby a roll may be removed by raising the roll out of its recess, swinging its lower end radially 110 and dropping it to disengage its upper end from its apertures.

3. An oilcloth stand comprising, a revoluble base having recesses constructed to receive and support the lower ends of the rolls, a plate mounted upon and above said base and having recesses therein constructed to receive and support the upper ends of the rolls, the rolls projecting through the upper plate, a cover or hood for the upper ends of the rolls mounted upon and supported by said plate, and clips secured to said cover and extending underneath said plate to hold said cover in position.

4. An oilcloth stand comprising a sup-

- port, a pair of upper and lower plates together with rods connecting said plates to form a braced revoluble carrier, said plates being adapted to support the rolls vertically at their upper and lower ends, a bracket mounted on and secured to said rods, and positioned intermediate said plates, a series of radially facing clamps mounted on said bracket and adapted to embrace and clamp the rolls intermediate their ends, and means for supporting said carrier vertically on said support.
5. An oilcloth stand comprising a support, a pair of upper and lower plates together with rods connecting said plates to form a braced revoluble carrier, said plates being adapted to support the rolls vertically at their upper and lower ends, a bracket mounted on and secured to said rods, a series of radially facing clamps mounted on said bracket and adapted to embrace and clamp the rolls intermediate their ends, a ring for securing said clamps in position on said bracket, and means for supporting said carrier vertically on said support.
6. An oilcloth stand comprising, a support, a pair of upper and lower plates together with means connecting said plates to form a braced revoluble carrier, said plates being adapted to support the rolls vertically at their upper and lower ends, a bracket revoluble with said carrier and positioned thereon intermediate said plates, a series of radially facing clamps mounted on said bracket and adapted to embrace the rolls, 35 and a post mounted on said support and extending through said carrier and vertically loosely through said lower plate and loosely through said bracket, and engaging said upper plate, adapted to suspend said carrier 40 on said support.
7. An oil cloth stand comprising upper and lower plates, means connecting said plates to form a braced revoluble carrier, a base for vertically supporting said carrier 45 for rotary movement thereon, said lower plate being constructed to support the lower ends of said rolls, and said upper plate having a plurality of apertures extending therethrough constructed to receive and support 50 the upper ends of the rolls, and a cover for the upper ends of the rolls projecting through said upper plate, whereby said rolls are supported at their upper and lower ends, and whereby a roll may be removed, with 55 said cover in position, by raising the roll, swinging its lower end radially, and dropping it to disengage its upper end from the aperture in the upper plate.

In testimony whereof I affix my signature 60 in the presence of these two witnesses.

JOHN L. MUELLER.
